[57] CLAIM

The ornamental design for a guitar, as shown and described.

DESCRIPTION

FIG. 1 is a front, left, perspective view of a guitar showing my new guitar;

FIG. 2 is a front elevation view thereof;

FIG. 3 is a top plan view thereof;

FIG. 4 is a left side view thereof;

FIG. 5 is a rear elevation view thereof;

FIG. 6 is a right side elevation view thereof;

FIG. 7 is a bottom plan view thereof;

FIG. 8 is a front, left perspective view of a second embodiment of FIG. 1;

FIG. 9 is a front elevation view thereof;

FIG. 10 is a top plan view thereof;

FIG. 11 is a left side view thereof;

FIG. 12 is a rear elevation view thereof;

FIG. 13 is a right side elevation view thereof; and,

FIG. 14 is a bottom plan view thereof.

The phantom line portions of the above drawings showing environment are for illustrative purposes only and do not form a part of the claimed design.

The broken lines which define the bounds of the claimed design form no part thereof.
